LIGHTING FIXTURE

Alden C. Wells, Kansas City, Mo.

Application November 22, 1940, Serial No. 366,605

4 Claims. (Cl. 240—6.4)

This invention relates to lighting fixtures of the automatic type combinable with a movable closure and adapted for operation thereby when the same is swung to and from the normal position.

One of the primary aims of this invention is to provide a unitary lighting fixture adaptable for use with and operable by a movable closure, such as a door, said fixture including as a part thereof, means for supporting one or more batteries to supply current to the lamp; a reflector that is combined with an arcuate, transparent lens; and an adjustable plunger, the length of which may be altered from time to time without disassembling the fixture or removing the same from the operative position.

A still further aim of this invention is to provide a lighting fixture of the aforementioned character that may be sold and installed as a single element and caused to operate when the door of a closet or similar room for example, is moved from the normally closed position toward the open position, said fixture having manually operable means for closing the circuit and therefore making the lamp burn when the said door is closed and the automatic switch, which is operated thereby, is in the open circuit position.

Other objects of this invention will appear during the course of the following specification, referring to the accompanying drawing, wherein:

Fig. 1 is an elevational view of the lighting fixture made in accordance with this invention and mounted for use.

Fig. 2 is a cross sectional view through the fixture taken on line II—II of Fig. 1.

Fig. 3 is a fragmentary sectional view through the fixture taken on line III—III of Fig. 2; and

Fig. 4 is a fragmentary sectional view illustrating a modified form of the invention.

It is common practice to light the interior of closets, cabinets or other comparatively inaccessible chambers, with lamps having electrical circuits closable when the closed door is swung to the open position.

This invention therefore, in its broadest aspect, contemplates the provision of a unitary lighting fixture that may be manufactured and assembled at a place remote from the point of use and installation, and positioned by one not necessarily skilled, without the employment of special equipment or affecting the building in any manner whatsoever. A solution to the presently existing problem therefore, has been discovered and when a lighting fixture made as shown in one embodiment of the invention, is created, the same may

be combined with the swinging door or closure 6 of any structure, broadly designated by the numeral 8.

In the drawing, closure 6 is assembled with the header 10 of the door casing 12. A stop 14 limits the swinging movement of closure 6 and when closure 6 and stop 6 and 14 are in abutting relation as shown in Fig. 2, the hereinafter described movable part of the fixture will be in the circuit opening condition.

The unitary fixture comprises a case 16, one section whereof is L-shaped in cross section. One leg of this L-shaped section of case 16, is secured to header 10 through the medium of screws or analogous fastening means 18, to maintain the other leg thereof in substantially parallel relation with closure 6 when the same is in the normal position. The other section 20 of case 16 is removable when the first mentioned L-shaped section is fastened to header 10.

A longitudinal groove 22 formed along one edge of section 20 engages lip 24 and a screw 26 joins the two sections of case 16 when the parts are assembled.

Section 20 has a concave reflector surface 28 through which is provided an opening 30 for the passage of lamp 32.

Grooves 34 and 36 in section 20 are formed along each longitudinal edge of the relatively long reflecting surface 28 and receive the longitudinal edges of a transparent lens 38 formed of transparent plastic. The width of lens 38 when the marginal edges thereof are not extended into grooves 34 and 36, is slightly greater than the shortest distance between these grooves and therefore, lens 38 is outwardly arched when in place. A cavity 40 is formed by the reflector surface 28 and lens 38 to house lamp 32.

This lamp 32 is screwed into an internally threaded opening formed in an inwardly and rearwardly angled ear 42, integral with the first mentioned section of case 16. A bushing 44 which lines the screwthreaded opening in ear 42 has a finger 46 integral therewith, that bears against the base of battery 48. Contact finger 50 secured to case 16 by screws 52, is in connection with lamp 32 and the positive contact point 54 of battery 56. A conductor 58 insulated from case 16 by blocks 60 is in engagement with the negative contact point of battery 56 at one end thereof, while the other end forms a contact point 62 disposed in the path of travel of movable bridging member 64.

Another conductor 66 insulated from and secured to case 16 through the medium of blocks 68,

has one end thereof in connection with positive contact point 70 of battery 48, while the other end establishes a contact point 72 in the path of travel of member 64. Member 64 is an integral part of bushing 74 slidably journaled in bearing 76 formed by the depending wall of case 16.

A plate 78 is in screwthreaded engagement with the end of bushing 74 opposite to member 64 and a compression spring 80 is interposed between plate 78 and depending wall of case 16 to move bushing and member 74 and 64 respectively, into the circuit closing position when door 6 is opened.

Plunger 82 in screwthreaded engagement with bushing 74, has the head 84 thereof in the path of travel of closure 6 to insure movement of member 64 from contact point 72 and 62 respectively, when closure 6 is against stop 14. Thus, when closure 6 is in the normal position, lamp 32 will not burn, but when closure 6 is swung open from the normal position, spring 80 will force member 64 against contact points 62 and 72 to close the circuit from batteries 48 and 56 respectively, to lamp 32.

In many instances, it is desirable to enter a compartment, close door 6 but still have light by causing lamp 32 to burn. In the modified form of the invention illustrated in Fig. 4, the circuit supplying current to lamp 32 from batteries 48 and 56, is modified by the introduction of a manually controllable switch that is independent of the automatic circuit making and breaking equipment. This manually operable switch may be moved to cause lamp 32 to burn while member 64 is at a distance from contact points 62 and 72.

The only modification that need be made in constructing the lighting fixture to embody this manually controllable switch is to break conductor 66 so that it presents a pair of contact points 100 and 102, bridged by slide 104. Button 106 projecting exteriorly of case 16 through slot 108, permits longitudinally moving slide 104 to position the same where the circuit is either opened or closed independently of the position of member 64.

With the condition present as illustrated in Fig. 4, the circuit is open and the lamp is not burning. Slide 104 is made of conducting material, but in this illustrated position, an area of insulating substance 110 on slide 104 bears against contact point 62. If the user enters the compartment and closes door 6, member 64 will be as seen in Fig. 4. The lamp 32 may be caused to burn by moving button 106 in the direction of the arrow, where insulating substance 110 is moved from contact point 62 and the latter caused to engage the main portion of slide 104. Thus, the circuit to lamp 32 will be closed through contact points 100, 102 and 62 being bridged by slide 104. The position of member 64 does not affect the operation of the parts of this auxiliary switch.

If it is desired to render the bridging of contact points 62 and 72 by member 64 ineffective, slide 104 may be moved through its full path of travel in the direction opposite to that indicated by the arrow, whereupon the section 103 of insulating material on slide 104 will rest upon contact 100 as contact point 62 remains on 110. When the parts are so placed, the closing of contact points 62 and 72 by member 64 is of no effect.

Batteries 48 and 56 may be quickly and easily replaced by lifting section 20 of case 16 from

position by the removal of screw 26. Resilient fingers 86 secured to case 16 embrace the batteries and yieldably hold the same in the operative position.

Obviously, unitary lighting fixtures embodying this invention and capable of employment with swinging closures, such as illustrated in the accompanying drawing, may be made to present physical characteristics different than that shown and described.

Having thus described the invention, what is claimed as new and desired to be secured by Letters Patent is:

1. In a unitary lighting fixture having a lamp and adapted for attachment to the horizontal under surface of a door header, a case having means for attachment to the header comprising an L-shaped section having an offset lip along the free edge of one side thereof; a flexible lens; and another section having a reflecting portion for the light rays from the lamp provided with a groove along one of its edges in engagement with said lip, said last mentioned section including a planar extension projecting from the reflecting portion in substantially parallel relation and spaced from the said one side of the L-shaped section, said extension being shorter than the one side of the L-shaped section whereby to dispose the reflecting portion at an angle to direct light rays downwardly and outwardly from the case, said reflecting portion being provided with an inwardly facing groove along each of two opposite edges thereof respectively for receiving two opposite marginal edges of the lens.
2. In a unitary lighting fixture having a lamp and adapted for attachment to the horizontal under surface of a door header, a case having means for attachment to the header comprising an L-shaped section having an offset lip along the free edge of one side thereof; a flexible lens; and another section having a reflecting portion for the light rays from the lamp provided with a groove along one of its edges in engagement with said lip, said last mentioned section including a planar extension projecting from the reflecting portion in substantially parallel relation and spaced from the said one side of the L-shaped section, said extension being shorter than the one side of the L-shaped section whereby to dispose the reflecting portion at an angle to direct light rays downwardly and outwardly from the case, said reflecting portion being provided with an inwardly facing groove along each of two opposite edges thereof respectively for receiving two opposite marginal edges of the lens.
3. In a unitary lighting fixture adaptable for use with and operable by a movable closure, a case having means for attachment to a support; a lamp mounted within said case; a battery within said case; a switch in said case comprising a member positioned to reciprocate substantially at right angles to the rearward side of said case and having an operating end portion exposed exteriorly of said side of said case; said case comprising an L-shaped section having a lip along

the longitudinal edge of one side thereof, sockets along the longitudinal edge of another side thereof, and an ear centrally located and angularly positioned inwardly from the one side and forward edge thereof to receive the said lamp; a flexible lens; another section comprising a concave longitudinal reflecting portion having an opening therein near its center larger than and formed to receive the said lamp, said other section having a longitudinal groove rearwardly of said portion and adjacent one edge thereof for receiving the lip of the said L-shaped section, and another longitudinal groove forwardly of said portion and adjacent the one edge thereof for receiving a marginal edge of said lens, said grooves being at substantially right angles to each other, said other section having a third longitudinal groove positioned forwardly of and adjacent the other edge of the said reflecting portion for receiving the opposite marginal edge of the said lens, said lens being of slightly greater width than the distance between the forwardly positioned grooves whereby the said lens will be transversely and outwardly arched when inserted into the said grooves, said other section having a planar extension rearwardly of the reflecting portion and in a plane substantially parallel to the said one side of the L-shaped section, said extension having fastening means projecting therethrough and into the said sockets.

4. In a unitary lighting fixture adaptable for use with and operable by a movable closure, a case having means for attachment to a support;

said case comprising an L-shaped section having a lip along the longitudinal edge of one side thereof, sockets along the longitudinal edge of another side thereof, and an ear centrally located and angularly positioned inwardly from the one side and forward edge thereof to receive the said light bulb; a flexible lens; another section comprising a concave longitudinal reflecting portion having a hole therein near its center larger than and formed to receive the said light bulb, said other section having a longitudinal groove rearwardly of said portion and adjacent one edge thereof for receiving the lip of the said L-shaped section, and another longitudinal groove forwardly of said portion and adjacent the one edge thereof for receiving a marginal edge of said lens, said grooves being at substantially right angles to each other, said other section having a third longitudinal groove positioned forwardly of and adjacent the other edge of the said reflecting portion for receiving the opposite marginal edge of the said lens, said lens being of slightly greater width than the distance between the forwardly positioned grooves whereby the said lens will be transversely and outwardly arched when inserted into the said grooves, said other section having a planar extension rearwardly of the reflecting portion and in a plane substantially parallel to the said one side of the L-shaped section, said extension having fastening means projecting therethrough and into the said sockets.
